UNITED STATES PATENT OFFICE.

PETER WEINGARDT, OF EMERSON, NEBRASKA.

SASH-HANGER.

980,577.

Specification of Letters Patent. Patented Jan. 3, 1911.

Application filed April 22, 1910. Serial No. 556,940.

To all whom it may concern:

Be it known that I, PETER WEINGARDT, a citizen of the United States, residing at Emerson, in the county of Dixon and State 5 of Nebraska, have invented certain new and useful Improvements in Sash-Hangers, of which the following is a specification.

This invention relates to improvements in sash-hangers, useful also for the purpose of hanging window screens, and has for its 10 object to provide a structure whereby the window sash may be maintained vertically and also may be supported in inclined relation to the window casing and may be 15 readily shifted from one position to another to increase or decrease the inclination.

The invention consists of the novel construction, form and arrangement of parts as described herein and claimed, and as 20 illustrated in the drawing, wherein,—

Figures 1, 2, 3 and 4 are views showing a single pair of sash-hangers used for the support of one side of the sash, Figs. 1 and 2 being respectively front and side views 25 of the frame-plate; Figs. 3 and 4 being, respectively, side and front views of the sash-plate. Figs. 5, 6, 7 and 8 are views showing a pair of sash-hangers employed for the support of the opposite side of the 30 sash; Figs. 5 and 6 being, respectively, front and side views of the frame-plate, and Figs. 7 and 8 being, respectively, side and front views of the sash-plate. Figs. 9 and 10 are vertical front views showing the parts when 35 assembled, Fig. 9 illustrating the parts shown in Figs. 1, 2, 3 and 4; and Fig. 10 illustrating the hanger members shown in Figs. 5, 6, 7 and 8. Fig. 11 is an end view of the assembled parts. Figs. 12, 13 and 14 40 are detail views showing parts of a vertical and a horizontal casing-strip, the horizontal strip being in section, and illustrating the use of a hanger for supporting a sash in inclined positions. Fig. 15 is a view of a 45 window frame and sash with my newly invented sash-hangers mounted thereon.

Referring now to the drawing for a more particular description, numeral 1 indicates a vertical strip of a window casing, and 2 50 a horizontal strip of the same, and upon the outer face of the vertical strip and near its upper end I secure a supporting member or frame-plate 3. Member 3 is an angular structure consisting of wings 4 and 5. Wing 5 is apertured at 6, and by means of keepers

7 the frame-plate may be secured as described.

At 8 is indicated a vertical recess or slot formed longitudinally in wing 4 and opening upon its upper end; at 9 is indicated a 60 recess formed adjacent to wing 5 and opening outwardly upon this slot.

At 10 is indicated a substantially horizontal recess or slot extending inwardly of wing 4, and opening upon its outer side. 65

The terminal of slot 8 is indicated at 11; the terminal of slot 10 is indicated at 12, and at 13, between terminal 12 and the opening of slot 10 is indicated an intermediate recess opening upwardly upon slot 10 and, outwardly of recess 13 is indicated a concavely-formed ledge 14 formed adjacent to slot 10 70 in the lower part of wing 4.

At 15 is indicated a sash-plate, the same being an angular structure and provided 75 with wings 16 and 17. Wing 17 is provided with apertures 18 and, by means of keepers 19 shown in Fig. 15, this hanger-member may be secured upon the sash 23. Wing 16 is provided with outwardly projecting studs 80 20 and 21, these studs being provided with heads or holders 22. Stud 20 is secured upon the upper part of the wing, stud 21 being secured upon said wing 16 intermediate its lower end and stud 20. 85

It will be noted that the hangers are employed in pairs, one pair being employed as a support for each of the vertical side-strips of the sash and while each pair of hangers operates substantially alike it will be seen 90 that the studs of the sash-plates are formed to extend outwardly from their outer sides. In practice, the sash-plates are secured upon the upper end of the sash and upon the "outdoor" side thereof, the sash being disposed 95 inwardly of the window casing, and the sash will be reliably supported by means of the hangers.

It will be understood that stud 20 is adapted to have a seating within slot 8 of the stationary hanger-member 3, and stud 21 is adapted to have a seating within slot 10; and in practice, when mounting the sash upon the casing, stud 20 is first inserted in slot 8, the sash at that time being manually 100 held at an angle with reference to the window casing, and as the lower end of the sash is lowered or swung toward the casing, stud 21 will enter slot 10; and when the sash is seated in a normal position the parts are 105 110

then disposed as shown in Fig. 12. At this time stud 21 will have a bearing at terminal 12 of slot 10, and stud 20 will be disposed within slot 8 intermediate recess 9 and the 5 upper end of wing 4; and, as is obvious, the sash will be detained by operation of the contacting parts of the hanger.

It is often desired to support a sash in an inclined position, and for this purpose the 10 operator may manually dispose the lower end of the sash outwardly of the window casing by swinging said lower end outwardly; and at this time, on account of the weight of the sash, stud 21 will pass downwardly and will occupy recess 13 of wing 4, and stud 20 will have a bearing at terminal 11; and the position of the parts will be as indicated in Fig. 13.

The function of recess 9 is to provide a 20 bearing for stud 20 at the time the operator elevates the sash for a mounting of said sash upon the casing, also for preventing the release of said stud from slot 8 when changing the position of stud 21 from a seating in concavity in ledge 14, while this stud passes 25 inwardly along slot 10.

It is often desired to support the sash in a position where the degree of inclination is greater than that indicated in Fig. 13 and, 30 for this purpose the operator, by slightly elevating or swinging the lower end of the sash outwardly, will cause stud 21 to pass partly outward of slot 10 and stud 21 will have a bearing within concavity in ledge 14 35 of wing 4, and at this time stud 20 will have a bearing at terminal 11 of wing 4.

The herein described sash-hangers are employed, principally, in connection with storm-windows and it is convenient, for ventilation 40 and other purposes, to provide different degrees of inclination for disposing the sash with reference to the window frame. When used in connection with window screens, it is often desired also to dispose the screens in 45 inclined relation. The pair of hanger-members illustrated in Figs. 1, 2, 3 and 4 are, for convenience, called the "left-hand" pair.

Numerals 3' and 15', respectively, indicate the two hanger-members of a pair for 50 use on the opposite or "right hand" side of the casing and sash. Sash-member 3' is formed with angular wings 4' and 5', wing 5' being provided with apertures 6' and wing 4' is provided with a slot 8', with a 55 terminal 11' and a recess 9' opening thereon, these parts being similar to those already described; slot 10' has a terminal 12' and recesses 13' and 14' are provided, the same as already explained. Wing 16' of sash-plate 60 15' is provided with studs 20' and 21', each having heads 22', and wing 17' thereof is provided with apertures 18'.

In the construction as described, when the sash is supported vertically the weight of

said sash is sustained by the lower stud 65 while seated at the terminal of the transverse slot. When the sash is partly inclined the lower stud supports the weight of the sash, while seated in recess 11. And, when the sash is disposed at its greatest inclination, its weight is sustained principally by the upper stud while seated at the terminal of the longitudinal recess, stud 21 resting in 70 concavity in ledge 14. Heads 22 of studs 20 and 21, operate as alining devices or guides 75 in conjunction with the studs and the walls of the slots, and aid in sustaining the sash-plates, so that the sash will not become dislodged while occupying the inclined positions mentioned. 80

Having fully described my invention, what I claim and desire to secure by Letters Patent is,—

1. A sash hanger, comprising a frame-plate having a wing formed with a vertical 85 recess opening upon its upper end and a substantially horizontal recess opening upon its outer side; a sash plate having a wing with an upper and a lower stud; said sash plate adapted to be supported by said frame 90 plate, said upper stud being disposed within and upwardly of the terminal of said vertical recess, the lower stud being seated within and at the terminal of said substantially horizontal recess. 95

2. A sash hanger, comprising a frame plate having a wing formed with a vertical recess opening upon its upper end and provided with a substantially horizontal recess opening upon its outer side with a communicating recess opening upwardly thereon: a sash plate having a wing with an upper and a lower stud, said sash plate adapted to be supported by said frame plate, its upper stud being disposed within said vertical recess, its lower stud being seated within the communicating recess of said substantially horizontal recess. 100

3. A sash hanger, comprising a frame plate having a wing formed with a vertical 110 recess opening upon its upper end and a substantially horizontal recess opening upon its outer side, and provided with a concaved ledge opening upwardly upon its outer side adjacent to the opening of said horizontal recess; a sash plate having a wing with an upper and a lower stud, said sash plate adapted to be supported by said frame plate, its upper stud being disposed at the lower 115 terminal of the vertical recess, its lower stud being seated upon said concaved ledge. 120

In testimony whereof I have affixed my signature in presence of two witnesses.

PETER WEINGARDT.
